UNITED STATES PATENT OFFICE.

ETHAN I. DODDS, OF PULLMAN, ILLINOIS, ASSIGNOR TO THE PULLMAN COMPANY, OF CHICAGO, ILLINOIS, A CORPORATION OF ILLINOIS.

CAST-METAL SIDE FRAME FOR TRUCKS.

No. 825,041.

Specification of Letters Patent.

Patented July 3, 1906.

Application filed October 30, 1905. Serial No. 285,155.

To all whom it may concern:

Be it known that I, ETHAN I. DODDS, a citizen of the United States, residing at Pullman, in the county of Cook and State of Illinois, have invented certain new and useful Improvements in Cast-Metal Side Frames for Trucks, of which the following is a specification.

In order to provide a cast-metal side for a railway-car truck which shall combine strength, light weight, and a pleasing appearance, I have invented a structure an approved form of which is described below, one of the salient features of which is the provision of hollow ribs extending over and part way down the sides of the pedestal portions.

Another object of my invention is the provision in the truck sides of means to permit the ready attachment of rods or the like to keep the journal-boxes and axles from leaving the sides in case the car becomes overturned and to tie together the two limbs of each pedestal portion.

In the accompanying drawings I have illustrated the preferred mechanical embodiment of my invention, wherein—

Figure 1 is an elevation of a side frame for a car-truck. Fig. 2 is a plan view of the structure shown in Fig. 1; and Fig. 3 is a vertical cross-section on line 3-3 of Fig. 1 as viewed in the direction indicated by the arrows.

The side frame comprises a main web or plate portion 10, having an integral bottom flange 11, extended outwardly from both sides of the plate portion 10, the ends of the flange terminating in recessed enlargements 12, open at the ends and bottom, a transverse hole 13 passing through the side and recess 15 at each end. The lower end of the outer limb of each pedestal portion 21 is supplied with a similar enlargement 14, having a recess 15 and transverse hole 16. A rod or similar device 15 (not shown) may be inserted in these recesses to prevent the journal-boxes and axles from leaving the side in case the car becomes upset and to tie the pedestal portions together, the bar being held in place by means of pins or bolts passing through holes 13 and 16. Plate portion 10 is also supplied with an integral top flange 18, extended outwardly from each side thereof, vertical ribs 19 joining the flanges 11 and 18 on each side of the main plate or web. Tapered hollow

ribs 20, the main portion of each of which is 55 cylindrical in cross-section, extend from the junctions of bottom flange 11 and end ribs 19 diagonally upward and over the pedestal portions 21, each rib projecting from both sides of plate portion 10 and extending part 60 way down the outer side of its pedestal, as at 20^a. Ribs 20 are tied together by the integral upper flange 18, and each is also supplied on its inner side with a plurality of holes 22, which are used when the side is cast to support the cores of the ribs and through which the cores may be afterward removed. A vertical rib 23 joins the outer end portions of each rib 20, with the adjacent enlargement 14 at the lower end of the pedestal, and each pedestal is also provided with a hollow spring-cap portion 24, as is clearly shown in Figs. 1 and 3. Bolts 25 are employed to fasten the transverse transoms (not shown) to the sides of the truck; and the tie-plates 26 and 27 are 75 riveted to the tops and bottoms of the side frames on opposite sides of the truck, for the purpose of securing them together.

It is to be understood that the parts of each side are all integral and that the structure is 80 produced by casting, whereby an economically-manufactured side frame results, having its metal disposed to attain a maximum of strength.

I claim—

1. A side for a car-truck having pedestals, a web or plate portion integral with and connecting said pedestals, and hollow ribs on said web or plate portion and integral therewith, each extending over and part way down the outer side of one of said pedestals, substantially as described. 85

2. A side for a car-truck having pedestals, a web or plate portion integral with and connecting said pedestals, and hollow ribs on said web or plate portion and integral therewith, each extending over and part way down the outer side of one of said pedestals, substantially as described. 95

3. A side for a car-truck having pedestals, a web or plate portion integral with and connecting said pedestals, and hollow ribs each integral with and projecting from both sides of said web or plate portion and extending over one of said pedestals, substantially as described. 100

4. A side for a car-truck having pedestals, a vertical web or plate portion connecting said pedestals having top and bottom flanges 105

- and hollow ribs, each of the latter extending from said lower flange over one of said pedestals, said top flange connecting said hollow ribs, substantially as described.
5. A side for a car-truck having pedestals, a vertical web or plate portion connecting said pedestals having top and bottom flanges, and hollow ribs each of the latter extending from said lower flange over one of said pedestals and part way down the outer side thereof, said top flange connecting said hollow ribs, substantially as described.
6. A side for a car-truck having pedestals, a web or plate portion integral with and connecting said pedestals, said portion having integral therewith top and bottom flanges extending from both sides thereof, vertical ribs on each side of said web or plate portion joining said top and bottom flanges, and hollow ribs, each projecting from both sides of said web or plate portion and extending over one of said pedestals, said top and bottom flanges connecting said hollow ribs, substantially as described.
25. 7. A cast-metal side for a car-truck having pedestals, a web or plate portion connecting said pedestals having top and bottom flanges, a plurality of ribs connecting said flanges, and hollow ribs joined to the junctions of said bottom flange and the outer ribs, each extending over one of said pedestals, substantially as described.
8. A cast-metal side for a car-truck having pedestals, a web or plate portion integral with and connecting said pedestals having integral top and bottom flanges, a plurality of integral ribs connecting said flanges, and integral hollow ribs joined to the junctions of said bottom flange and the outer ribs, each extending over and part way down the outside one of said pedestals, substantially as described.
9. A side for a car-truck having pedestal portions integral therewith and a recess in each of the two limbs of each pedestal portion extending upwardly from the lower surface thereof for the reception of means to prevent the journal-boxes and axles from leaving the side and to tie the two limbs together, substantially as described.
10. A side for a car-truck having pedestal portions integral therewith and a recess in each of the two limbs of each pedestal portion for the reception of means to prevent the journal-boxes and axles from leaving the side and to tie the two limbs together, said side being provided with transverse holes therethrough, each intersecting one of said recesses, substantially as described.

ETHAN I. DODDS.
